DRIER

**Francis R. Ackerman, Euclid, and William Isler,
Cleveland Heights, Ohio**

Application April 1, 1940, Serial No. 327,278

3 Claims. (Cl. 34—151)

This invention relates to driers, but has reference more particularly to a portable drier which is especially adapted for use in drying articles hung for drying in closely spaced parallel lines.

It is customary during the fall and winter season, instead of hanging outdoors for drying purposes, articles which have been laundered in the home, to hang them in the same room in which they are been laundered, usually the furnace room.

Where the usual type of coal-fired hot air furnace is used, such furnace ordinarily provides sufficient heat radiation to dry the laundered articles fairly rapidly, so that, for the average size family, the entire wash may be washed, dried and ironed in a single day.

Where, however, gas or oil-fired heating units are employed, such as those combining a burner and a boiler, or a burner, and a warm-air furnace, as in modern air-conditioned homes, the heat radiation from such units in the furnace room is usually so small as to be entirely inadequate for rapidly drying laundered articles, so that frequently, it becomes necessary to do the washing on one day, permit the wash to remain on the lines overnight, and do the ironing the following day. This, of course, is usually translated into increased laundry costs.

Recently there have come into use, especially in modern homes, where the furnace rooms are small, due to the desire to utilize a portion of the basement for a recreation room, devices which are designed to facilitate the hanging of the entire family wash within a relatively small area. Such devices usually include a pair of spaced pipes, rods, or other supporting members, supported from the ceiling of the furnace room by means of brackets or the like, and, in turn, supporting a fairly large number of parallel clothes lines, spaced approximately six inches apart.

The use of such devices has suggested the device or apparatus of the present invention, the principal object of which is to dry the wash rapidly and thoroughly, and in a fraction of the time required to dry the same in the ordinary manner.

A further object of the invention is to provide a device of the character described which is portable and therefore readily moved to any desired position for use, or moved to an out-of-the-way corner, when not in use.

A further object of the invention is to provide a device of the character described which is compact and efficient and which can be readily manufactured in desired quantities at relatively low cost.

A still further object of the invention is to provide a device of the character described, which is so constructed as to utilize the warm air or hot water or vapor from the furnace itself, thereby dispensing with the necessity of a separate heating unit.

Other objects and advantages of the invention will be apparent during the course of the following description.

10 In the accompanying drawings, forming a part of this specification, and in which like numerals are employed to designate like parts throughout the same,

Fig. 1 is a front elevation of one form of a drier constructed in accordance with the present invention;

Fig. 2 is a side elevation of the drier of Fig. 1;

Fig. 3 is a cross-sectional view of the drier taken on the line 3—3 of Fig. 1;

20 Fig. 4 is a fragmentary perspective view, showing the manner in which the drier is used.

Fig. 5 shows an electrical heating unit, which may be used in a modified form of the drier;

Fig. 6 shows a coil which may be used in a still further modification of the drier; and

Fig. 7 is a perspective view of a modified form of the drier, and showing the manner in which it is suspended from a device for facilitating the hanging of the wash, such as has been referred to above.

Referring more particularly to Figs. 1, 2, 3 and 4, the drier comprises a base 1 having rollers or wheels 2 mounted thereon, adjacent the corners thereof, whereby the drier may be readily moved about to any desired position. Mounted on the base 1 adjacent the forward edge of the base, is a hot air distributor, comprising an upstanding rectangular frame-like portion 3 and a rearwardly extending frusto-pyramidal portion 4, 35 which communicates with such portion 3 and has extending rearwardly therefrom a cylindrical duct 5 which is closed at its rear end. A second duct 6 intersects and communicates with the duct 5.

40 Within the frame-like portion 3 of the distributor are a multiplicity of transversely spaced vertically-extending louvers or vanes 7, which are preferably of V-shaped cross-section, and which serve to deflect and concentrate the hot air, so as to cause it to pass through the relatively narrow 45 slots or openings 8 between the louvers, in the direction indicated by the arrows in Fig. 3.

The duct 5 is supported by means of a pedestal 9 and platform 10, such platform further serving to support a small electrical motor 11, the shaft 50 12 of which extends through the rear of the duct

5 and into such duct, being provided at its forward end with a fan 13.

Journalled within and extending transversely of the frustro-pyramidal portion 4 of the hot air distributor is a shaft 14, which may be rotated by means of a handle 15, and to which is rigidly secured a deflector plate 15', the purpose of which will be presently described.

Telescopically mounted on the duct 6 is a collar 16, having a flange 17, whereby the collar may be slid up or down. The collar 16 is provided in its upper end with a bayonet slot 18, whereby the collar may be engaged with a pin 19 which extends from a duct 20, in order to establish communication between the ducts 6 and 20. The duct 20 is provided with a manually-operable damper 21, whereby the duct may be opened or closed to any desired extent.

The duct 20 is preferably an auxiliary duct which extends from one of the hot air ducts of the furnace in the furnace room, and may be made of a number of telescoping parts, so that it may be moved up out of the way when not in use.

In the use of the drier, the drier is moved to a position, as shown in Fig. 4, adjacent the ends of the lines of wet articles S, T, etc., which are to be dried, the slots or openings 8 being preferably aligned with the spaces between such lines of articles. The collar 16 is then slid upwardly and connected with the duct 20, after which the damper 21 is opened to permit the passage of hot air into the duct 6. The fan 13 is then started, forcing the hot air into the distributor and out through the openings 8, and through the spaces between the lines of wet articles, causing such articles to be dried rapidly and efficiently. By moving the damper 15 upwardly or downwardly, the hot air may be directed upwardly or downwardly, as desired.

Where fans are used in conjunction with hot air furnaces, as in winter air-conditioning systems, such fan may be used to project the hot air through the drier, thereby obviating the need for the fan 13.

In a modified form of the invention, where hot air, hot water or vapor is not available, an electrical heating unit 22, such as shown in Fig. 5, may be used. Such unit will preferably be placed within the duct 5, immediately in advance of the fan 13.

Where the hot water or vapor is available a coil 23, such as shown in Fig. 6, may be used, and may be placed in the duct 6.

If desired, the portion 4 of the distributor may be in the form of the frustum of a cone or sphere, and the ducts 5, 6 and 20 of rectangular cross-section, instead of round.

Referring to Fig. 7 of the drawings, a device for facilitating hanging of the wash, such as has been briefly referred to, comprises pairs of spaced brackets 25, designed to be secured to the ceiling of the laundry room, and provided with clamp brackets 26 which supports rods 27 between which the clothes lines are strung, and a rod 28, upon which the drier may be suspended in clothes-drying relation with the lines of clothes by means of hooks 29. The drier 30, in this case, is identical with the other forms of driers which have been described, with the exception that it is unnecessary, in view of the fact that the drier is in suspension, to provide a platform and rollers therefor. The drier 30 may be provided with a flexible conduit 31 adapted to be connected to one of the warm air pipes 32 of the heating system. When not in use, the drier may be disconnected from the warm air pipe and removed from the rod 28, for storage purposes.

It is to be understood that the form of our invention, herewith shown and described, is to be taken as a preferred example of the same, and that various changes in the shape, size and arrangement of parts may be resorted to, without departing from the spirit of our invention, or the scope of the subjoined claims.

Having thus described our invention, we claim:

1. In combination with means to support clothes, suspended, in horizontally spaced rows, a drier movable towards and away from said rows, said drier including an air distributor having a plurality of spaced parallel vertically extending vanes, the spaces between said vanes adapted to be aligned with the spaces between said rows, and means for forcing air through said vanes.

2. In combination with means to support clothes, suspended, in horizontally spaced rows, a roller-supported carriage movable towards and away from the ends of said rows, and a hot-air distributor mounted on said carriage, said distributor having a plurality of spaced vertically-extending vanes, the spaces between said vanes adapted to be aligned with the spaces between said rows, and for forcing air through said vanes.

3. In combination with means to support clothes, suspended, in horizontally spaced rows, a drier disposed adjacent the ends of said rows, said drier including an air distributor having a plurality of spaced parallel vertically extending vanes, the spaces between said vanes being aligned with the spaces between said rows, and means for forcing air through said vanes.

FRANCIS R. ACKERMAN.
